Patented Aug. 15, 1922.

FIG. 2.

FIG. 3.

FIG. 1.

Inventor:
Harriet Lajors Redmond
By Emery, Booth, James and Sawyer
Attys.

UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

INFANT'S BAND.

1,425,899.

Specification of Letters Patent. Patented Aug. 15, 1922.

Application filed June 7, 1921. Serial No. 475,809.

To all whom it may concern:

Be it known that I, HARRIET LYONS REDMOND, a citizen of the United States, and a resident of Boston, in the county of Suffolk and State of Massachusetts, have invented an Improvement in Infants' Bands, of which the following description, in connection with the accompanying drawings, is a specification, like characters on the drawings representing like parts.

This invention relates to infants' bands. In order that the principle of the invention may be readily understood, I have disclosed a single embodiment thereof in the accompanying drawing, wherein—

Fig. 1 is a plan view of the band with the ends attached and viewed from the rear;

Fig. 2 is a similar view, but looking at the band from the front;

Fig. 3 is a plan view of the band in its open condition; and

Fig. 4 is a transverse section on the line 4—4 of Fig. 1 of the band in its assembled position with the ends thereof secured together.

The band as an entirety is represented at 1. While said band may be of any suitable material, it is preferably knitted, and the wales 2 thereof preferably extend lengthwise of the band. The entire band desirably has a binding 3 formed in some suitable way, as, for instance, by an overseaming or similar sewing operation providing an edge which is substantially equally expansible longitudinally with the band itself. The band, when constructed as described, is of comparatively little elasticity in a lengthwise direction, but is of relatively high elasticity in a transverse direction.

One end of the band, and in this instance the end 4, is formed substantially straight and has secured thereto one or more tapes, strips or ribbons indicated at 5, which desirably constitute loops. At a suitable point lengthwise of the garment, it is provided with one or more transversely extending slits or openings 6—6 which may be of any desired extent, and which desirably are reenforced about their edges, as by an overseam or like stitches 7. Within the scope of my invention, any suitable number of openings 6 may be provided, but preferably I provide two, which are respectively at the upper and

lower edges of the garment extending toward each other a suitable distance, as, for example, about one inch in the completed garment.

The end of the band opposite the end 4 is provided with one or more strips or extensions 8, 8 which desirably are integral with the body of the band, and which in the embodiment of my invention herein disclosed are two in number. The number of strips or extensions 8 should correspond to the number of openings 6. The said strips are of any suitable length and are herein shown as each about one quarter of the length of the main portion of the band. They may, however, be of any suitable length, but should be so proportioned that after the band has been placed as herein described about the infant, the ends of the band may be secured with sufficient tightness to hold it in place.

At or adjacent the ends of the strips 8, I provide fastening means herein shown as tapes or ribbons 9, 9, which are intended to be tied to the similar parts 5. While I have referred to tapes or ribbons 5 and 9 as the securing means, it is to be understood that any other suitable securing means may be provided, and that in certain cases I may use button and button-hole means, the buttons being provided either upon the ends of the extensions 8, or at or near the end 4, and the button-holes being upon the other part.

In using the garment, the infant is laid preferably face up upon the band spread out as indicated in Fig. 3. The two ends of the band are then passed about the infant, the strips 8 being passed through the openings 6, so that the band entirely encircles the infant, which is then turned over upon its back or upon its face, as the case may be, and thereupon the ends 8 are brought onto the end 4, and the two sets of tapes or ribbons 5, 9 are tied together, as indicated in Fig. 1, thus quickly securing the band in position and so that it will hold in place.

I have referred to the tapes or ribbons 5 as desirably in loop form. This construction is desirable in that when the band is secured about the infant, there are thus in effect provided at one end of the band double the number of fastening means that would otherwise exist. In other words, at the end 4 there are provided four tape or

ribbon ends secured to the end 4 at spaced points, so that the pull is from all four points and not from merely two points.

While the opening or openings 6 may be constructed in any suitable manner, it is desirable that the material overlap at the outer edges, as indicated most clearly in Figs. 3 and 4. Viewing said figure, it will be noted that the parts 10, 10 slightly overlap the underlying parts and that they are secured in position by the seaming or stitching 3. This affords a stronger construction at the outer ends of the slits 6. To provide this construction, the slits 3, in the process of manufacture, desirably extend to the upper and lower edges of the band, respectively, and thereafter the material at both sides of each slit are overlapped and secured as desired.

Having thus described one illustrative embodiment of my invention, I desire it to be understood that although specific terms are employed, they are used in a generic and descriptive sense and not for purposes of limitation, the scope of the invention being set forth in the following claims.

Claims:

1. An infant's band having a pair of slits at the upper and lower edges thereof, in alignment but spaced apart, the material at the outer ends of said slits being secured in overlapping relation whereby said outer ends of the slits are reinforced, a pair of strips extending from one end only of the band at the upper and lower edges thereof, said strips being adapted to be passed through said slits, tapes or ribbons secured

to the ends of said strips, and a corresponding number of double tapes or ribbons in looped form secured to the opposite end of 40 the band and adapted to be tied together to secure the band in place.

2. An infant's band composed of knitted material having the wales extending lengthwise the band, the latter having two slits 45 respectively extending inwardly from the upper and lower edges of the band, a pair of longitudinal extensions integral with the band and each having a tape secured thereto, and a pair of tapes secured in looped 50 form to the end of the band opposite said extensions, the tape of one of said extensions and one of the pair of looped tapes respectively being adapted to be tied together to secure the band in place, whereby 55 the pull on said opposite end of the band is distributed over twice the number of points that there are ties.

3. An infant's band composed of knitted material having wales 2 extending lengthwise of the band, seaming 3 for the periphery thereof, a pair of slits 6 extending inwardly from the upper and lower edges of the band, and having parts 10, 10 secured in overlapping relation by said seaming 3, a 60 pair of extensions 8, 8 adapted to be passed through said slits and having securing means 9 at their ends and corresponding securing means 5 at the opposite end of said band.

In testimony whereof, I have signed my name to this specification.

HARRIET LYONS REDMOND.
